UNITED STATES PATENT OFFICE.

LEONARD MILLER, OF BROWNWOOD, TEXAS, ASSIGNOR TO BOY STEPHANUS BOYSEN,
OF BROWNWOOD, TEXAS.

DISTRIBUTING SWITCH MECHANISM FOR ELECTRIC SIGNS AND SIMILAR DEVICES.

1,104,692.

Specification of Letters Patent.

Patented July 21, 1914.

Application filed September 19, 1911. Serial No. 650,263.

To all whom it may concern:

Be it known that I, LEONARD MILLER, a citizen of the United States, residing at Brownwood, in the county of Brown and State of Texas, have invented new and useful Improvements in Distributing Switch Mechanism for Electric Signs and Similar Devices, of which the following is a specification.

10 My present invention relates to improvements in switch mechanisms adapted for use in connection with changeable electric signs, exhibitors, and analogous devices, and it has for its object primarily to provide an automatic distributing switch which may be used in connection with the sign or similar device and its flasher whereby a flasher of comparatively small size and having a relatively small number of switch contacts may 15 be used to operate a sign having a multiple number of groups of illuminating sections, and the expense and other objections incident to the leading of a large number of wires to the sign from the flasher which is 20 usually located at a considerable distance from the sign, are obviated, and, moreover, a flasher of small size and less cost can be used.

To these and other ends, the invention 25 consists in certain improvements, and combinations and arrangements of parts, all as will be hereinafter more fully described, the novel features being pointed out particularly in the claims at the end of the specification.

In the accompanying drawings:—Figure 1 is a diagrammatic view showing the manner of arranging an automatic distributing switch embodying the present invention 30 with respect to an electric sign and its flasher; Fig. 2 is a bottom plan view of the distributing switch, a portion thereof being broken away to illustrate the arrangement of switch contacts; Fig. 3 is an edge view 35 of the cover of the switch showing the switch contacts in end elevation; Fig. 4 is a perspective view of the component parts of each switch unit; Fig. 5 is a perspective view of a portion of the movable switch 40 blade or member; Fig. 6 represents a horizontal section of a part of the distributing switch showing the switch operating mechanism; Fig. 7 represents a vertical section 45 of the distributing switch showing the switches in end elevation, and also illus-

trating the mechanism for actuating the switches; Fig. 8 represents a section through the distributing switch at right angles to the plane of the section in Fig. 7. Figs. 9 and 10 show another embodiment of the invention whereby all the switches may be opened simultaneously after they have all been closed successively.

Similar parts are designated by the same reference characters in the several views.

In the accompanying drawing, I have shown a distributing switch which is especially adapted to be used between an electric sign and its flasher whereby a flasher of relatively small size and capacity may be used in connection with a sign having a large or multiple number of groups of illuminating units or sections. This embodiment of the invention is generally preferred, although it is to be understood that modifications and changes may be made in the details or in the relative arrangement of the parts thereof in order that the invention may be carried into practice advantageously to meet different requirements. In the present instance, the distributing switch comprises a suitable box or casing 1 having a top or cover 2 which in the present instance is utilized as a support for the various switch contacts. Any suitable number 35 of switches may be used and each switch may embody any desired number of contacts, it being understood that one contact of each switch corresponds and is connected to an illuminating unit or section of the 40 sign. In the present instance, the distributing switch mechanism embodies three switches 3, 4 and 5, and as shown, the construction of each switch is substantially the same and, hence, a detail description of one 45 switch will be sufficient. A set of current conducting strips 6 are arranged at the under side of the cover or support 2, these strips being of a number corresponding to the number of contacts employed by each 50 switch. These current conducting strips 55 are connected electrically to binding posts 7 which are preferably arranged on the upper side of the cover. The binding posts 7 serve as terminals for the distributing 60 switch mechanism and are connected to corresponding contacts of the flasher 8 by a set of conducting wires 9. The group of wires 9 which may be in the form of a cable corresponds in number to the number of contacts 65 in the switch mechanism.

tacts employed by the flasher and to the number of binding posts or terminals 7 of the distributing switch mechanism, although as will hereinafter appear, the sign contains a number of illuminating sections which is a multiple of the number of wires 9 and the contacts of the flasher and all of the illuminating sections or units of the sign may be operated from the flasher. The switch unit of each distributing switch in the present instance embodies a brush 10 one end of which lies in close and electrical contact with the under side of the corresponding conducting strip 6, while its opposite or free end is bent downwardly at an angle, an insulating washer 11 is applied beneath the brush 10, a second brush 12 is applied to the under side of the insulating washer 11 and is in substantial parallelism with the brush 10, and a metal plate 13 is applied to the under side of the brush 12, a binding screw 14 being passed through the several parts and through the cover or support 2 and may be then attached to a binding post 15. The insulating washer 11 preferably has a sleeve 16 to insure proper insulation between the binding screw 14 and the conducting strip 6 and the brush 10.

In the present instance, electrical connection is made between the brushes 10 and 12 of the several switch units by a switch member 17, this switch member being preferably composed of a strip of fiber or other suitable insulating material provided on its face with a number of contact plates 18 which correspond in number and arrangement to the pairs of brushes 10 and 12. This insulated switch plate is mounted on a rock shaft 19 and the rock shaft is journaled in suitable bearings 20 which are arranged at opposite ends of the shaft and are secured to the under side of the cover or support 2. The shaft 19 also has an actuating arm 21 fixed thereto and this arm is connected to an actuating rod 22.

In the operation of the distributing switch mechanism, the switches are operated successively and in order to close and open the circuits through these switches. Different means may be provided for operating the switches in this manner. In the present instance, the operation of the switches in the proper order is accomplished electrically and automatically by the flasher, the switch actuating means comprising a shaft 23 which is journaled in bearings 24 carried by a suitable bracket secured to the bottom of the casing, and this shaft is provided with a set of cranks 25, the wrist pins of which are spaced equidistantly in a circumferential direction. The actuating rods 22 of the several switches are connected to the wrist pins of the respective cranks 25 so that during one revolution of the shaft 23, these switches will be closed and opened in predetermined

order. Turn-buckles 26 are provided for the rods 22 in the present instance in order to provide for proper adjustments of the switches. The shaft 23 receives a progressive or step-by-step rotation from a toothed disk or wheel 27 which is fixed thereto, a pawl 28 which is pivotally mounted on a pawl-carrying arm 29, the latter being mounted to swing about the shaft 23 as an axis and an operating lever 30, the latter being pivotally connected to the pawl-carrying arm at 31, and is fulcrumed at 32 to a stationary standard 33 and its free end is operatively connected to the core 34 of a solenoid, the coil 35 of which is suitably secured within the casing and has its terminals connected to the binding posts 36 and 37. A spring-pressed ratchet dog 38 serves to coöperate successively with the notches in the disk or wheel 27 and thereby hold the shaft 23 in different positions corresponding to the closed positions of the distributing switches, the shaft being rotated into these different positions by the pawl 28 which is lifted each time the coil of the solenoid is energized and is lowered when the coil of the solenoid is deenergized, gravity in the present instance serving to restore the pawl and coöperative parts to initial position after each operation.

The binding post 15 for the switch unit of each switch is connected to an illuminating unit or section of the sign 39 which may be of any suitable construction and is shown diagrammatically in Fig. 1, the binding posts 15 of each distributing switch, however, being preferably grouped and a group of wires 40 serves to connect the group of binding posts of each switch with a corresponding group of illuminating units or sections of the sign. The binding post 36 which is connected to one terminal of the solenoid coil is connected by a wire 41 to a suitable contact controlled by the flasher, whereby the solenoid will be energized and deenergized between the lighting of the different groups of illuminating units or sections of the sign, the other terminal 37 of the coil 35 being connected by a wire 42 to the line wire 43 which serves as a common return for the illuminating elements of the sign.

Flashers of different kinds may be used in connection with a distributing switch mechanism embodying the present invention, it being usual to employ flashers which successively illuminate or "spell out" the words, letters or lines of the sign. In the present instance, the sign contains twenty-four illuminating units or sections which may correspond to letters, words, lines or designs. By using the distributing switch mechanism, however, a flasher having only eight contacts ^{8a} may be used, for the illuminating units, and a contact 41^a for the sole-

noid circuit, the flasher also having a moving contact controlling member 8^b operating in the usual way, for example toward the right (Fig. 1), to successively engage the contacts 8^a and thereby illuminate successively the units or sections of the sign which are connected to the binding posts 15 of one switch, it being understood that this switch at this time is closed and the other switches 10 are open, and after all of the units or sections of the sign connected to the binding posts 15 of this particular switch have been illuminated, the member 8^b reverses its motion, disengaging from the contacts 8^a and 15 41^a, thereby extinguishing the corresponding units of the sign and deenergizing the solenoid. Upon the next movement of the member 8^b toward the right, (Fig. 1) this member first engages the contact 41^a whereby the 20 solenoid coil is energized and the latter operates to rotate the shaft 23 and thereby open the switch which was previously closed and to close the switch next in order, the continued movement of the member 8^b of the 25 flasher operating to illuminate another set of units or sections of the sign, and in this way, the operation is continued automatically until the entire sign has been illuminated, whereupon the entire operation of the 30 system is repeated. The distributing switch is simple in construction and may be placed close to or on the sign, thereby minimizing the length of the multiple number of wires which connect the distributing switch mechanism to the sign. The flasher may be placed 35 at any suitable point and it is only necessary to lead a comparatively small number of wires thereto.

In some case it may be desirable to close 40 the switches successively as before, to light or illuminate the parts or sections of the sign in order, and to open the switches simultaneously to extinguish the whole sign. The mechanism shown in Figs. 9 and 10 is 45 adapted to operate in such manner, the main switch operating shaft 23^a in this instance having a set of cranks 44 of a number corresponding to the number of switches to be operated, and these cranks are, as before, 50 arranged by suitable angles about the shaft 23^a. Each switch 45 in this instance has its actuating rod 46 connected to a lever 47, the latter being pivoted at one end to the top of a frame 48 while the opposite end of this lever 55 is adapted to rest upon the shoulder 49 of a latch 50 pivoted at its lower end to a suitable support 51. Each lever 47 cooperates with a corresponding crank 44, there being one lever for each switch and one latch 60 for each lever, the different levers and latches being capable of independent movement, and each latch has a spring 52 which serves to hold it in locking engagement with its respective lever. A latch-releasing bar 65 53 is provided, it lying against the rear sides

of the different latches, and it is supported by pivoted arms 54. This releasing bar also has an arm 55 which is operatively connected to the core of a solenoid or magnet 56.

In this form of apparatus, rotation of the shaft 23^a causes the cranks to press against and lift successively the different levers, thereby successively closing the corresponding switches, each lever as it is lifted being locked in elevated position by its respective latch, and hence all the switches will be held in closed condition. After all the switches have been closed, the solenoid 56 is energized by current transmitted thereto at appropriate intervals from the flasher 8, the releasing bar then acting to simultaneously release all the latches and permit all the switches to open. In this way, the different parts or elements of a sign may be illuminated in order and the entire sign may be extinguished simultaneously.

I claim as my invention:—

1. The combination of an electrical sign or exhibitor embodying a plurality of groups of illuminating units, a flasher for controlling the illumination of the units of said groups, and a distributing switch mechanism for establishing operative relation between said flasher and the different groups of illuminating units of the sign or exhibitor, embodying a plurality of groups of contacts corresponding to the groups of illuminating units, the contacts of each group being connected respectively to the units of the corresponding group of illuminating units, a switch blade for each group of contacts having separate contacts adapted to engage all of the contacts of the respective group simultaneously, a shaft common to and cooperative with all of the switch blades and embodying means for operating the switch blades successively when rotated, and electro-magnetic means controlled by the flasher for rotating said shaft.

2. The combination of an electrical sign or exhibitor having a plurality of groups of illuminating units, means for controlling the illumination of the units of said groups, and distributing switch mechanism governed by said controlling means and operative automatically to successively set the different groups of units in operative condition, embodying a plurality of groups of contacts for the corresponding groups of illuminating units, the contacts of each group being connected respectively to the units of the corresponding group of illuminating units, a single switch member having separate contacts adapted to engage the contacts of the respective group, a shaft common to and cooperative with all the switch members, and electro-magnetic means controlled by the flasher for rotating said shaft and thereby operating the switch members.

3. The combination of a plurality of

- switches, each switch embodying a set of contacts and a switch member each switch member having separate contacts and operative to simultaneously engage and disengage the contacts of the respective set, and a single rotary shaft common to and coöperative with said switch members for closing said switches successively, electro-magnetic operating means for rotating said shaft, and devices for retaining the different switch members in predetermined relations after each operation of said electro-magnetic means.
4. The combination of an electrical sign or exhibitor embodying a plurality of groups of illuminating units, a flasher capable of rendering said units operative successively, and a distributor interposed between and electrically connected to the units of the sign and the flasher embodying a plurality of switches, one for each group of illuminating units, each embodying a set of contacts connected individually to the units of the respective group of illuminating units and a switch member having a set of separate contacts to engage the contacts for the illuminating units, a shaft common to and coöperative with all the switch members to close the respective switches successively, and electro-magnetic means controlled automatically by the flasher and connected to operate said shaft to close said switches successively and thereby render different groups of the units of the sign operative successively.
5. The combination of an electrical sign embodying a plurality of groups of illuminating units, a flasher capable of rendering the units of the sign operative successively, and a distributor for controlling the operation of the different groups of units embodying a multiple contact switch for each group of units of the sign, the contacts of each

switch being connected in separate circuits between the flasher and to the illuminating units of the corresponding group, a rotating shaft common to and coöperative with all of said switches, and electro-magnetic means controlled automatically by the flasher for operating said shaft to govern the operation of the different groups of illuminating units of the sign.

6. A distributing switch mechanism embodying, in combination, a plurality of switches, each switch embodying a set of contacts and a switch member adapted to simultaneously engage the respective set of contacts first-mentioned, a shaft having cranks coöperative with the different switch members and adapted when rotated to successively close and open the contacts corresponding thereto, a solenoid operatively connected to said shaft to rotate the same at each energization, and a flasher having contacts controlling the circuits through the contacts of each switch and also controlling the operation of the solenoid.

7. A distributing switch mechanism embodying in combination a set of conducting strips, a plurality of switches each embodying a plurality of pairs of contacts, one, of the contacts of each pair for each switch being in electrical engagement with one of said conducting strips, separate terminals for the other contacts of said pairs, and means for successively closing said switches.

In testimony whereof I have hereunto set my hand in presence of subscribing witnesses.

LEONARD MILLER.
